CABINET FOR A TELEPRINTER OR THE LIKE

Berndt Ebbe Frick, 9 Herrgårdsvägen,
135 00 Tyresö, Sweden

Filed Apr. 24, 1972, Ser. No. 247,236

Claims priority, application Sweden Oct. 22, 1971

Term of patent 14 years

Int. Cl. D18—99

U.S. Cl. D64—11 R

FIG. 1.

FIG. 2.

FIG. 3.

FIG. 1 is a front perspective view of a cabinet for a teleprinter or the like showing my new design;

FIG. 2 is an inverted rear perspective view; and

FIG. 3 is an inverted rear perspective view from the left.

I claim:

The ornamental design for a cabinet for a teleprinter or the like, substantially as shown.
